UNITED STATES PATENT OFFICE.

THOMAS HENRY BURCHELL, OF NEW YORK, N. Y.

DESIGN FOR A WRITING-SHIELD.

SPECIFICATION forming part of Design No. 26,758, dated March 16, 1897.

Application filed January 25, 1897. Serial No. 620,689. Term of patent 14 years.

To all whom it may concern:

Be it known that I, THOMAS HENRY BURCHELL, a citizen of the United States, and a resident of the city of New York, in the county 5 and State of New York, have invented and produced a new and original Design for a Writing-Shield, of which the following is a specification, reference being had to the accompanying drawings, forming part thereof, 10 and in which—

Figure 1 is a front elevation of a writing-shield incorporating my design. Fig. 2 is a rear elevation of same, and Fig. 3 is a sectional view of same on the dotted line 3-3 of Fig. 1. 15 The leading features of my design consist of the form and configuration of the writing-shield, substantially as illustrated in the accompanying drawings.

The external front face A of the writing-

shield is substantially rectangular in outline, 20 except at its upper end, where it is rounded, as indicated at B, and at its rear side the corresponding wings C C of the writing-shield are parallel with the body of same, except at points adjacent to their lower ends, where 25 they, as indicated at E E, incline rearward at an angle from said body. The upper edges of the wings C are inclined, as at F.

What I claim is—

The design for a writing-shield, substantially as shown and described.

Signed at New York, in the county and State of New York, this 22d day of January, 1897.

THOMAS HENRY BURCHELL.
